UNITED STATES PATENT OFFICE.

CHARLES H. TRASK, OF LYNN, MASSACHUSETTS.

SOLE OR HEEL TRIMMING MACHINE.

SPECIFICATION forming part of Letters Patent No. 357,743, dated February 15, 1887.

Application filed October 4, 1886. Serial No. 215,254. (No model.)

To all whom it may concern:

Be it known that I, CHARLES H. TRASK, of Lynn, in the county of Essex and State of Massachusetts, a citizen of the United States, have 5 invented a new and useful Improvement in Sole or Heel Trimming Machines, of which the following is a full, clear, and exact description, reference being had to the accompanying drawings, forming a part of this specification, in explaining its nature.

My invention relates to the organization in one machine of two groups or series of trimming devices, each of which comprises a sole-edge trimmer, with or without a welt-cutter, 15 and with suitable guides for presenting the work thereto, a shank-edge trimmer, with or without a welt-cutter, and with suitable guides for presenting the work thereto, and a heel-edge trimmer, with or without a rand-cutter, 20 and with suitable guides for presenting the work to it or them, the two series or groups of trimmers being so arranged in relation to each other and to the frame of the machine that they may be turned simultaneously by the 25 same pulleys, or, in other words, so that two boots or shoes may be trimmed at the same time.

It further relates to an organized machine for trimming the soles and heels of boots and 30 shoes, having a frame or stand and shafts mounted thereon and extending from both sides thereof, each of which is adapted to carry or support at both ends a trimming-tool, and to the arrangement and location of the ends of 35 the shafts and trimming-tools in relation to each other and to the frame of the machine, whereby two sets or groups of devices may be simultaneously used.

It further relates to the employment or use 40 in this duplex or twin machine of a number of shafts extended from each side of a common support and adapted to receive and operate reversible trimmers—that is, trimmers adapted to be used alternately or successively upon 45 each side of the machine.

It further relates to the combination and arrangement of the various shafts extended from each side of a common frame, each shaft supporting at each end a trimmer of the same 50 character, adapted for the same kind of work, with pulleys and a single belt, whereby the two gangs or groups of trimming devices are

simultaneously operated by one operating mechanism.

It also relates to a reversible or double trimmer having two cutting or trimming surfaces, one of which is adapted to be used upon one end of its holding-shaft, and the other of which is adapted, upon reversing the trimmer, to be used upon the other end of the same shaft.

It further relates to various details of organization and construction, all of which will hereinafter be referred to.

In the drawings, Figure 1 represents, in front elevation, the upper portion of the head of a 65 duplex or twin sole and heel trimming machine containing the features of my invention. Fig. 2 is a view thereof in side elevation. Fig. 3 is a plan view of the machine. Fig. 4 is a view in side elevation of a double or two-part 70 sole-edge trimmer. Fig. 5 is a side elevation thereof. Fig. 6 is an end elevation thereof. Fig. 7 is an end elevation of a double or two-part heel-edge trimmer. Fig. 8 is a side elevation thereof. Fig. 9 is a vertical section 75 thereof. Fig. 10 is a view in section to illustrate the relation of a rand-trimmer, rand-guard, and top-list guide and rest, and the heel-rest to the double or two-part heel-edge trimmer. Fig. 11 represents in section the 80 double or two-part sole-edge trimmer and the guides and parts adjacent thereto and used therewith. Fig. 12 shows in section a double or two-part shank-edge cutter upon one end of an operating-shaft. Fig. 13 is a view in 85 section of the rand-guard used upon each end of the heel-trimming shaft. Fig. 14 is an end elevation of a double or two-part shank-edge trimmer. Fig. 15 is a side elevation thereof. Fig. 16 is a view in elevation of the rand and 90 counter guide of the heel-trimming device.

Referring to the drawings, A is the post or stand of the machine. a is a head bolted to the post or stand, and which supports the shafts and various operating devices, as hereinafter indicated. The first shaft in order is the sole-edge-trimmer shaft a', which extends across the head a and from each side thereof, as represented in Figs. 1 and 3. It is of a length to bring its ends into proper position 100 in relation to the sides of the head and to the ends of the heel-trimmer shaft and the shank-edge-trimmer shaft. The said sole-edge-trimmer shaft carries at one end the sole-edge

trimmer a^2 and at its opposite end the sole-edge trimmer a^3 . The second shaft in order—namely, the heel-edge-trimmer shaft a^4 —has suitable bearings in the head a , and its ends extend therefrom, and each end occupies upon its respective side of the head a suitable relation to the other shafts and trimmers used therewith; and this shaft supports at one end the heel-trimmer a^5 and at its opposite end the heel-trimmer a^6 . The third shaft which the head supports or has bearings for is the shank-edge-trimmer shaft a^7 . (See Figs. 1, 2, and 3.) This shaft, like the shafts a^2 a^4 , extends across the head and from each side thereof, and supports at one end thereof the shank-edge trimmer a^8 and at its opposite end the shank-edge trimmer a^9 . The head may support another or fourth shaft, a^{10} , which, like the other shafts above named, extends across the head and from each side thereof, to bear or support at one end a grinding-wheel, a^{11} , and at its opposite end a grinding-wheel, a^{12} . This shaft, however, may be dispensed with.

The shafts and the trimmers which they support are simultaneously rotated by a belt, B , which passes over the pulley b on the grinding-wheel shaft a^{10} , the pulley b' on the sole-edge-trimmer shaft a^4 , the pulley b'' on the heel-trimmer shaft a^4 , and the pulley b^3 on the shank-edge-trimmer shaft a^7 ; and each of the two sole-edge trimmers has these elements associated with it—namely, the welt guide or gage c , which is fastened by a headed stud, c' , to its respective end of the shaft a^4 , and a shield or cover, c^2 , which comprises a plate having a recess, c^3 , in its front of sufficient depth to cover the greater part of a single sole-edge trimmer or a double sole-edge trimmer, if one be used. It has a hub or extension, c^4 , which fits the shaft a^4 , and provides a wide bearing thereon, an arm, c^5 , which has a hole, c^6 , fitting the steady-rod c^7 , upon which it is movable. The plate also has the inclined curved or rounded surface c^8 , which serves as a support for the sole, and the under part of which has a rest for the hand or finger of the operator while steadyng the shoe as it is presented to the trimmer, and especially during the trimming about the toe. The plate is movable away from the trimmer upon the shaft a^4 and supporting-rod c^7 , to uncover or expose it, in opposition to the spring c^9 , which surrounds the shaft a^4 and bears against the shoulder c^{10} and the end of the hub c^4 . The same adjuncts are used with each of the sole-edge trimmers.

I would here say that each sole-edge trimmer has a welt-trimming surface integral with it. Each of the heel-edge trimmers a^5 a^6 has a rand-edge cutter, d , and rand-guard d' , which is formed or provided by the outer edge of the disk D , and each disk is fastened to its respective end of the shaft a^4 by means of the headed stud d^2 . Each heel-trimmer also has a top-lift guide, d^3 , and top-lift rest d^4 , and a heel-rest, d^5 . The top-lift rest d^4 and guide d^3 , preferably, are formed upon the plate d^6 , having a hole of sufficient size to receive a section or

part of the trimmer, or, when a double or two-part trimmer is used, that part which is not called into use until reversed or used upon the other end of the shaft. This plate d^6 is fastened to another plate, d^7 , by means of screws and slots, so as to be laterally movable thereon. The plate d^7 also has a large hole of sufficient size to receive the heel-trimmer, as above stated. It has an arm, d^8 , which has a long sleeve, d^9 , formed thereon and fitted to the supporting-rod d^{10} , upon which it is arranged to slide or move in opposition to the spring d^{11} , which surrounds the rod and bears against the surface of the head and the inner end of the sleeve d^9 . The plate d^7 also supports or carries the heel-rest d^5 , which may be made adjustable or movable in relation thereto horizontally at a right angle to the plane of rotation of the cutter by means of the rods d^{12} d^{13} and a spring, d^{14} , and nut d^{15} . The plate d^7 also has an arm, d^{16} , which bears upon a guide or cam, d^{17} , carried by a stud or support, d^{18} . This cam d^{17} governs or controls the position of the top-lift rest and guide in relation to the trimming-edge of the trimmer during the lateral movement of the plate d^7 and the top-lift rest and guide supported thereby in relation to the rand-guide, it being understood that these parts are movable laterally to expose sufficient of the cutting-surface of the trimmer to the work as the length of the section of the heel to be trimmed increases, and the spring d^{11} serves to move the plate, and therefore the top-lift rest and guide, in a reverse direction as the length of the section of the heel being trimmed decreases.

The position of the two shank-edge trimmers a^8 a^9 is well shown in Figs. 1 and 2, and they are fastened to the end of their supporting-shaft by a headed stud, and the welt-trimmer is formed integral with the shank-edge trimmer, as with the sole-edge trimmer, which may be covered or not in use by a covering-sleeve similar to that described in my application for Letters Patent of the United States, Serial No. 204,324, filed June 7, 1886.

I would here say that the various devices or guides for presenting the work to the various trimmers are shown and described and claimed in various of my pending applications—namely, No. 204,324, filed June 7, 1886, Nos. 205,202, 205,203, and 205,204, filed June 15, 1886, and No. 209,198, filed July 27, 1886—and that I do not claim specifically the said devices herein. I would further say that I do not limit the invention, so far as these features are concerned, to the devices herein specified, as there are other guides and rests which may be used with the various trimmers for the purpose of governing the presentation of the work thereto.

The post or stand A also supports blowers E E' , (shown in dotted outline in Figs. 1 and 2,) which are attached to a common shaft, e , and rotated from the main shaft by the belts e' and pulleys e^2 . The blower E is arranged to draw the shavings and dust from the left

group of trimmers and the blower E' the dust and shavings from the right group.

All the double or two-part trimmers have these features in common—first a double or two-part cutting-surface, one section of which is adapted for use upon reversing the trimmer upon the same shaft, or by moving it from the end of a shaft upon one side of the head to the end upon the other side, in which case, however, the trimmer would not be reversed. Of course, if it is reversed the position of the operator in relation to it must be changed in order that it may cut properly. The trimmers are also made, preferably, integral throughout. Their cutting-edges are also formed by recesses which extend the entire length of the trimmer—that is, from one end to the other—so that a double or two-part trimmer can be made about as quickly, and almost as cheaply, as an ordinary solid single trimmer.

Of course each trimmer preserves its individual characteristics.

I will first describe the double or two-part sole-edge trimmer. This is well shown in Figs. 4, 5, and 6. It is made from a solid block of metal of sufficient width to furnish two cutting-sections, $f'f'$. Each of these cutting-sections has a welt-cutter, f^2 , and a sole guard or rest, f^3 . To form the cutting-edges of the trimmer, recesses f^4 , extending entirely across the trimmer, are formed and the section f^5 of the trimmer are reduced from the cutting-edges f^6 backward sufficiently to make the cutting-edges most distant from the center of the trimmer. The trimmer, as completed, will have its two cutting-surfaces oppositely arranged to each other, and a simple reversal upon the same end of the shaft will not bring the other section or part of the trimmer into operation for practical use unless the operator changes his position to the other side of the shaft.

The heel-trimmer is well represented in Figs. 7, 8, and 9. It is made from a solid block of metal, the interior of which is removed to form the recesses $g'g'$ and the section g^2 , which is centrally arranged and has a hole, g^3 , for the reception of the shaft. The cutting-edges g^4 are formed by recesses g^5 , which extend inward from the edge of the trimmer, as represented in Fig. 7, and the outer surfaces of the section which form the cutters are cut away sufficiently to bring the cutting-edges into proper prominence. The trimming-surface of this cutter need not be double the width of two separate trimmers, as its trimming-edge may be so shaped that the central portion of the trimmer may be used in common. It will be seen that this trimmer has cutters extending from both sides of a common support, and that the cutters are integral with this common support, and that the spaces or recesses g^5 extend inward and open into cavities $g'g'$.

The shank-edge trimmer is shown in Figs. 12, 14, and 15. It is also made from a solid block of metal. It has the cutting-surfaces $h' h'$, one of which is adapted to be used at one

end of its operating-shaft and the other upon the opposite end of such shaft. Each cutting-section has cutters h^2 of proper form, and welt-cutters h^3 , and the recesses h^4 , which form the teeth or cutters, extend entirely across the trimmer, and the two cutting edges or surfaces are opposed to each other, as in the two other trimmers.

By using a grinding-wheel shaft and grinding-wheels on each end thereof, and appropriate supports, m , for presenting the cutters thereto, a saving in time of grinding the cutters is obtained.

In use the machine may be arranged so that the trimmers of one group shall be shaped for one style of work, and the trimmers of the other group for a different style of work. This change in the form or shape of the trimmer-cutter occurs less frequently in the heel-trimmer than in the other trimmers. When the machine is thus prepared, a single operator is enabled to do a variety of work without stopping to change his trimmers; or two operators can be working simultaneously upon different styles of work, one upon one side of the head of the machine and the other upon the other side.

By using a two-part or double trimmer less time is employed in sharpening the trimmers, as the two-part trimmer of the construction specified can be sharpened about as quickly as an ordinary single trimmer, and in use one part or section of each trimmer is first employed, and they are then removed and transposed to the other ends of their respective shafts, and the other cutting-sections of the trimmer then brought into position for use, and they are used until the cutters are dull, when they are reground and used as before.

It is obvious that by this construction or duplex organization several very important requirements are met and advantages obtained. In the first place, there is great economy in floor-space of a factory effected, because, instead of four, five, or six separate machines with their independent belts, there is but a single machine, having a capacity of four, five, or six, using not much more space than one ordinary heel-trimming machine occupies, and, second, there is a very great saving in the cost of construction. The twin or duplex organization enables me to use but one stand and one head, and one set of operating devices to secure the practical results of four, five, or six separate machines. There is also the saving in time in the trimming operation, as the trimmers are so arranged that the various trimming operations are successively performed upon the same shoe by the same operator, doing away with the change in position and the frequent transfer of the work required where separate machines are used. There is also the advantage which arises from giving one machine three or four times the capacity of the ordinary trimming-machine, whereby the machine may be employed simultaneously upon two boots or shoes. Another advantage arises

from the duplex cutters, and this relates not only to the cost of manufacture, which is but slightly more than that of a single trimmer, but to the operation as well, for they can be used twice as long without grinding.

It will be seen that the shafts have bearings upon each side of their respective pulleys, and that the pulleys are centrally arranged upon the shafts, and the shafts are equally balanced at each end, so that they can be rapidly rotated with great steadiness, and the machine be very evenly balanced.

I would say that it is not always necessary to use the shank-edge trimmers, in which event the machine as organized would have two groups of trimmers, each presenting a sole-edge trimmer and a heel-edge trimmer.

It will be seen that the disk d , upon which the rand-guide d' is formed, is adapted to rotate with the shaft a' , and that its surface x is shaped to act as a counter guide or support for the counter of the boot or shoe while the heel is being presented to the trimmer.

I intend to apply for a separate patent for the cutter-head here described, and hence have claimed it now only in combination with a horizontal revolving shaft in a sole and heel trimming machine.

Many of the details of this machine are shown and described, but not claimed, in the form herein claimed in other applications now pending in the Patent Office, and bearing the serial numbers 205,202, 205,203, 205,204, and 204,324; and the application now pending, No. 35 205,202, shows more clearly than the present and claims the sliding heel-rest and its cam adjustment.

Having thus fully described my invention, I claim and desire to secure by Letters Patent 40 of the United States—

1. The combination of the double or two-part heel-trimmer in one piece, having two trimming-sections, with a shaft, a' , each end of which is adapted to receive and hold the trimmer, whereby its cutting-sections may be successively used, substantially as described.

2. The combination of the double or two-part sole-trimmer in one piece, having two trimming-sections, with a shaft, a' , each end of which is adapted to receive and hold the trimmer, whereby its cutting-sections may be successively used, substantially as described.

3. The combination of the double or two-part shank-edge trimmer in one piece, having two trimming-sections, with a shaft, a' , each end of which is adapted to receive and hold

the trimmer, whereby its cutting-sections may be successively used, substantially as described.

4. The combination of the rotary heel-trimmer, having double cutting-sections located one at the side of the other and adapted to be successively used, with the top-lift guide d' and top-lift rest d^2 , substantially as described.

5. The combination of the rotary heel-trimmer, having double cutting-sections located one at the side of the other and adapted to be successively used, with the heel-rest d^2 , substantially as described.

6. The combination of the rotary heel-trimmer, having double cutting-sections located one at the side of the other and adapted to be successively used, with the top-lift rest and guide and heel-rest and a rand-guide, substantially as described.

7. The combination of the rotary heel-trimmer, having double cutting-sections located one at the side of the other and adapted to be successively used, with a top-lift rest and guide movable lengthwise the cutter, substantially as described.

8. The combination, substantially as described, of the rotary heel-trimmer, having double cutting-sections located one at the side of the other and adapted to be successively used, with a rand-cutter, substantially as described.

9. The combination of a rotary trimmer, having trimming edges or cutters of twice the length of the edge of the work to be trimmed, with a plate having a hole or recess for covering the rear section of the trimmer not in use, and the surface of which plate is concaved for use as a finger-guide in the presentation of the work to the operative surface of the trimmer, substantially as described.

10. A duplex sole and heel trimming machine having one set of shafts, each shaft of which has tool-carrying ends, and the two sets of duplex trimming-tools, each of the several shafts whereof has its two tool-carrying ends extended laterally from the frame of the machine, and the edge-trimming shaft of which is extended farther at each end than the heel-trimmer shaft, whereby a right and left handed presentation of work is permitted on the same machine and a cheaper and lighter machine made for the same work.

CHARLES H. TRASK.

In presence of—

F. F. RAYMOND, 2d,
J. M. DOLAN.
